CONTAINER CLOSURE AND COMBINATION
Herbert F. Wheaton, Summit, and Stanley J. Koll, Keansburg, N.J., assignors to American Flange & Manufacturing Co. Inc., New York, N.Y., a corporation of Delaware

Filed Feb. 11, 1964, Ser. No. 344,131
1 Claim. (Cl. 215—46)

This invention relates to closure caps for container openings and is particularly concerned with such caps formed of lightweight metal, which while capable of being fixedly applied for effectively closing and sealing the openings of bottles, jars, cans and the like are nevertheless easily and safely destructible for hand removal without the use of tools.

This application is a continuation in part of application Ser. No. 325,817, filed Nov. 25, 1963, now Patent No. 3,258,149, in the names of Herbert F. Wheaton and Stanley J. Koll and entitled, "Closure Cap and Method of Manufacture," wherein there is disclosed an invention in closure caps and the method of making the same which caps, though effectively sealing the openings of bottles, jars, cans and the like against considerable pressure, may be readily and safely removed by destroying them by hand action in the manner provided for and without the use of any tools. Large numbers of such caps, embodying that invention, have been manufactured and tested and though the results thereof have been highly satisfactory and the invention has added a substantial step forward in the art, there is nevertheless room for improvement on it. That step is added by the subject of the instant invention.

In the closing and sealing of containers such as bottles, jars and cans with bottle type finishes, particularly where those containers carry commodities under pressure and are closed by a closure cap made out of lightweight metallic sheet material such as aluminum, a close structure balance must be maintained in the cap in order to provide effective sealability while nevertheless enabling removal and destruction of them through hand gripping and tearing along a tear strip. To be fully effective, the material and the forming and securing of it must be such that the customer can grasp the tearing ear between his fingers and destroy the cap by tearing along the scores without having to be previously educated to follow any particular motion. The scoring and forming of the cap must be such that this hand tearing can be easily commenced and proceeded with in uniform easy manner but the cap must, nevertheless be devoid of fractures in the score formed by cupping the cap from the scored blank or drawing the cap skirt inwardly and forcing it downwardly in the course of applying it to a bottle. Practically all of these characteristics have been introduced into the cap of the aforesaid application Ser. No. 325,817, but experience in the removing of large numbers of them, after they have been fully secured to bottles, has brought out that in certain instances an unexpected resistance has to be overcome to commence the tearing. This might be just enough to discourage some customers who, on having a little difficulty in their first effort to remove the cap, might condemn it forever. On investigation it has been found that in the forming of the cap blank of the aforesaid parent application, the edge notch provided on either side of the tearing ear, though specially provided for assisting in assuring performance of the inconsistent functions of tight securing and ready removal, seems to have imparted a characteristic to the finished cap which, in certain instances, provided a little hindrance to removal.

It is accordingly the province of the instant invention to eliminate such hindrance while, at the same time, retaining the strong securing characteristics of the aforesaid

2

cap. Also a slight unsightliness of appearance introduced by the hindering factor just mentioned has also been removed. Though these improvements have been achieved by incorporating a feature that might at first blush be thought to be a weakening one, it has advantageously been found that no such weakness occurs.

It is accordingly a principal object of the invention to improve upon the removal characteristics of hand actuated destructible capseals.

Another object is to provide such improvement in removability without weakening the securing effect.

A further object is to provide for such removability, with effective securing, while enhancing the appearance of the secured cap.

Further and more detailed objects will in part be obvious and in part be pointed out as the description of the invention, taken in conjunction with the accompanying drawing proceeds.

In that drawing:

FIG. 1 is a plan showing of a flat cap blank notched and scored in accordance with the invention disclosed in parent application Serial No. 328,817.

FIG. 2 is an elevational view of a cap, formed from the blank of FIG. 1, applied to a container neck.

FIG. 3 is a greatly enlarged fragmentary plan view of the flat cap blank of the invention showing the novel notch configuration embodied therein.

FIG. 4 is a greatly enlarged fragmentary section of a scored portion of the finished cap skirt as viewed internally thereof.

FIG. 5 is a part sectional, part elevational view of a cap, in accordance with invention, in place on a container neck but in unsealed condition.

FIG. 6 is an elevational view similar to FIG. 5 of the cap taken after the cap has been sealed in place on the container neck.

FIG. 7 is a view similar to FIG. 4, but utilizing straight scoring.

Considering first the general aspects of the closure cap of the invention as shown in FIGS. 5 and 6, the cap generally indicated at 1 comprises a flat disc-like top 2 surrounded by a depending skirt 3 with the juncture of the top and skirt indicated at 4. The skirt 3 terminates in a downwardly facing free edge 5, which edge except for the position where the gripping ear, generally indicated at 6, is located. The ear 6 extends downwardly for a short distance at 7 forming a continuation of the skirt then turns generally radially outwardly away from the cap skirt in a slight outward and downward incline. The ear 6 is provided with side edges 8 and 9 which taper slightly inwardly towards each other throughout their extent from the free edge of the skirt to the rounded end portion 10.

The surface of the cap 1 is provided with a pair of line-like weakened sections, such as formed by either internal or external scores, whichever is desired. These scores extend for a substantial portion of the distance across the cap top and have portions 11 and 12 as seen in FIGS. 3 and 5 which extend across the juncture 4 of the top and skirt and then, in substantially parallel relationship, down the skirt 3 at 13 and 14. Accordingly a tear strip 15 is formed as a continuation of the ear 6, which strip extends across the cap occupying that space lying between the score lines.

Turning now to FIGS. 1 and 2, a flat cap blank 20 and an applied cap 21 formed therefrom are shown embodying the improvements disclosed in application Ser. No. 325,817. These improvements include providing a flat cap blank 20 with a pair of score lines having portions 22 and 23 extending substantially across the cap top area 24, portions 25 and 26 which extend across the line of

junction 27 between the top area 24 and the surrounding skirt-area 30, and portions 28 and 29 extending across the area 30 to form the cap-skirt portion. In this form of scoring it can be seen that the score portions 25 and 26 are aligned with the side edges 31 and 32 of the ear 33. Then they diverge outwardly away from each other with the portions 28 and 29 terminating a short distance, indicated at 34 and 35 respectively, from the base of the notches 36 and 37.

In the forming of a cap out of the flat blank 20, even without the step of securing it in place on a bottle neck, the metal of the skirt portion 30 is rather severely worked by progressively reducing its diameter from the line 27 out to the blank periphery as the portion 30 is moved into lateral position. The flared score portions 28 and 29 are moved inwardly toward each other so as to become substantially parallel and in alignment with the sides 31 and 32 of the ear 33. The provision of the notches 36 and 37 serves several purposes. First they provide a place into which the metal can flow as its diameter is reduced. This eliminates the reaction of crowding which would otherwise take place with consequent likelihood of weakening the metal behind the scores. By terminating the notches in abrupt pointed metal parts 38 and 39, it was intended that when the notches closed up during the skirt forming operation, barely perceptible almost completely closed slits would be formed extending to the free edge of the skirt on either side of the ear. This works well and the short un-scored portions 34 and 35 are protected against fracture though being the one portion of the metal left to pucker they are thus weakened. They do however protect their scores against fracturing at their commencement through accidental movement of the ear while not introducing a block of any substance against intended tearing away of the strip extending from the tearing ear portion 33 and the skirt portion 30.

When however such a cup is applied to a bottle, as seen in FIG. 2, by rolling or spinning the cap-skirt inwardly into sealing engagement with the bottle neck, a problem is created. This securing calls for further reduction of the diameter of the previously formed skirt whose notches 36 and 37 have already been fully closed up. Further inward movement of the skirt 30 then only serves to cause an overlapping of the metal onto the tear strip portions 31a and 32a as indicated at 40 and 41 in FIG. 2. To a substantial extent this overlapping is caused by the presence of the pointed parts 38 and 39. This overlapping, as can be readily seen from the showing in FIG. 2, interferes with the easy commencement of the tearing action by making it necessary to first pull the ear 33 laterally away from the bottle a sufficient amount to free it from the overlap before one can commence tearing along the score lines. The lateral outward pulling on the ear causes the metal flaps 40 and 41 to stick out and to present a possible source of injury if the removed cap is left lying around.

To remedy the above described problem, the cap 1 formed in accordance with the invention is provided with a new and novel notch configuration as shown in the flat blank 50 illustrated in FIG. 4. The blank 50 is shown for purposes of illustration as having the same type of flared scoring imparted thereto as employed in the cap of FIGS. 1 and 2 which includes score lines extending across the cap top 2, over the juncture 4 between the top and skirt, out across the skirt 3, in portions 13 and 14, and terminating in spaced relationship, as indicated at 51 and 52 respectively, from the notches 53 and 54. Of primary importance in the showing of FIG. 4 is the particular configuration given to the notches 53 and 54. Specifically, the notches are formed respectively with radiused base portions 55 and 56, inner side portion 57 and 58 from which extend the respective side edges 8 and 9 of the ear 6, and outer side portions 59 and 60. Here it is to be noted that the side portions 59 and 60 merge into the skirt portion edge, or blank periphery, 5 in smooth

radiused portions 61 and 62. More specifically the blend radius of curvature to produce the curves 61 and 62 between the outer sides of the notches and the blank periphery is at least one-half the radius of curvature of the notch base portions 55 and 56. This relationship has been found to give the best result in accomplishing the objects of the invention in the finished and applied cap as hereinafter explained.

From the showings of the finished cap of the invention in FIGS. 4 and 5, it can be appreciated that during the drawing of the skirt 3 laterally away from the top 2, the notches, only one of which is shown in FIG. 4, become slits which remain partially open in the portion thereof approaching the skirt edge 5. Thus the upper portion of each notch is closed up into a completely closed slit as indicated at 63; then, in the downward vertical extent of the slit towards the skirt edge 5, it opens up in the curve 64 extending away from the inner tear strip side of the slit indicated at 65. Thus a pair of downwardly extending outwardly flared openings 66 and 67 are formed at the lower edge portions of the skirt, one at either side of the ear 6. Once the cap is so formed from the blank, the manufacturing of it is completed by the application of the lining or gasketing as indicated at 68.

FIG. 5 shows the completed cap 1 of the invention seated in place on a standard bottle finish prior to the securing of it thereon. The bottle 70 here shown is provided with a straight upstanding neck 71 terminating in a dispensing mouth surrounded by an annular bead 72 having an upper face 73, an outwardly and downwardly curved outer face 74 and an inwardly and downwardly curved lower face 75. From this showing it is clearly seen that the cap skirt 3 extends down to a position below the lower face 75 of the bead 72 with its lower edge portion extending free of the neck 71 and being completely unsupported thereby.

With the cap in the FIG. 5 position, the securing operation is carried out by bringing the bottle into position beneath a spinning head having a plurality of rollers for engaging the free portion of the cap skirt. Two of such rollers are indicated at 80 and 81. The spinning head is moved downwardly and when it reaches the limit of its downward movement, the rollers are in the FIG. 5 position. Advantageously some means are incorporated in the spinning head for pressing the ear down against the bottle. As the head rotates, the rollers, such as 80 and 81, move radially inwardly forcing the lower skirt portion in against the bottle. This further decreases the skirt diameter causing an additional deformation and movement of the skirt metal. As the skirt, without any backup support, is moved radially inwardly by the individual spaced rollers, wrinkles or undulations are formed therein. These wrinkles are ultimately ironed out when the rollers reach the limit of their radial movement where they firmly roll the skirt against the lower bead face 75 and neck 71 of the bottle. However, the skirt material making up these wrinkles must go somewhere. The still somewhat open slits 66, increasing to graduated extent due to the curve 64, provide just the space that is needed. The resulting formation of the secured cap is as pictured in FIG. 6 where it can be readily seen that the flared openings 66 and 67 present in the cap before the securing is effected are now completely closed up into barely perceptible slits 66 and 67. There is no overlapping of the skirt material with respect to the ear and the whole skirt and aligned ear portion present a neat smooth appearance.

Going back and summarily considering FIGS. 3, 4 and 6, it can be seen that the particular configuration imparted to the notch in the flat blank is such that each increment of curvature of the rounded portions 61 and 62 providing the curve 64 provides a corresponding increase in the notch width as it approaches the periphery of the blank. This increase in notch width is in direct

proportion to the subsequent decrease in skirt diameter and corresponding movement of metal to close up the notch. Thus since the final skirt diameter required to effectively seal the cap onto a container is only partially reached when the cap is in the form of FIGS. 4 and 5, the slit there shown is only partially closed. When, however, the cap skirt is rolled inwardly about the container neck to its final minimum diameter, the notch is closed up the remaining amount into the hairline slits of FIG. 6.

Consequently none of the objectionable features found in the cap as shown in FIG. 2 remain. Specifically there are no overlapping protrusions or flaps in the cap of the invention shown in FIG. 6 to resist the outward movement of the tear strip portion 15 lying between the closed slits 16 and 17. Also the likelihood of one being injured through handling of the cap after its removal, has been eliminated, for not only have the sharp outwardly projecting flaps caused by the pointed portions 38 and 39 been eliminated, but those pointed portions have been replaced by curved portions 61 and 62 which retain some of their original curvature as indicated at 18 and 19 in FIG. 6. Most importantly, however, is the fact that through the teaching of the invention herein disclosed a substantial step forward is made toward increasing the ease with which a metal tear-off cap can be removed from a container without any corresponding decrease in effectiveness or sealability of the closure.

FIG. 7 shows an alternative flat cap blank incorporating the improved notch configuration of the invention. The blank here shown, however, instead of embodying the improved flared scoring of application Ser. No. 315,817 is provided with a pair of straight parallel score lines, one of which is shown at 90, extending straight across the skirt portion of the blank all the way into the base of the notch at 91. The cap thus formed, even though lacking the improved scoring arrangement shown in conjunction with the cap blank of FIG. 4, still possesses the advantages offered by the slits 16 and 17 of FIG. 6.

Though, in the foregoing, a particular form of tear-off closure having weakened lines for facilitating that tearing has been shown and described, it is to be understood that the invention is not to be considered as being limited by the particulars of that showing. Numerous variations such as in the size and shape of the closure or the container to which it is applied would become apparent to those skilled in the art and could be employed without departing from the spirit and scope of the invention. Also the formation of other score patterns in the metal

including either inside or outside scoring and doing so in other manners would not be considered a departure from the spirit and scope of the invention. Accordingly, it is, of course to be understood that the foregoing description taken in conjunction with the accompanying drawing are for illustrative and not for limiting purposes.

Having described our invention, what we claim as new and desire to secure by Letters Patent is:

In closure cap construction, a flat substantially circular blank adapted to be formed into a cap having a disc-like top portion, a laterally depending skirt depending from and around said top portion, a pair of spaced weakened tearing lines in said top and skirt and a tearing ear extending outwardly away from the lower edge of said skirt formed as an integral extension of that portion of said cap skirt lying between said weakened lines, said blank comprising an annular peripheral cap skirt portion, an inner circular cap top portion, a flat tearing ear having exposed side edges extending radially outwardly from a peripheral edge portion of said blank, a pair of weakened lines extending at least part way across said top portion and continuing outwardly into said skirt portion, said weakened lines terminating radially inwardly of said blank periphery on either side of said ear, and a pair of radially inwardly extending notches formed in the periphery of said blank on either side of said ear, said blank periphery forming a circular line interrupted by said ear and notches, each of said notches having an inner side, an outer side and a concavely curved base connecting said inner and outer sides, the side edges of said ear forming tangent continuations of the curved base of said notches at the inner sides thereof, the outer sides of said notches connected to said circular blank periphery by a smooth convex curve and the radius of said smooth convex curve is at least one-half as great as the radius of curvature of the base of said notch.
